UNITED STATES PATENT OFFICE.

REED A. TERRY, OF OMAHA, NEBRASKA.

DESIGN FOR A SKIRT-GAGE.

42,654.

Specification for Design.

Patented June 18, 1912.

Application filed November 22, 1911. Serial No. 661,871. Term of patent 7 years.

To all whom it may concern:

Be it known that I, REED A. TERRY, a citizen of the United States, residing at Omaha, in the county of Douglas and State of Nebraska, have invented a new, original, and ornamental Design for a Skirt-Gage, of which the following is a specification, reference being had to the accompanying drawing, forming a part thereof.

Figure 1 is an end view of a skirt gage showing my new design. Fig. 2 is a front

view of the skirt gage, and Fig. 3 is a plan view of the same.

I claim:

The ornamental design for a skirt gage, as shown.

In testimony whereof I have affixed my signature in presence of two witnesses.

REED A. TERRY.
